UNITED STATES PATENT OFFICE.

JULES DUBOIS, OF BROOKLYN, NEW YORK.

WATCH-CASE.

SPECIFICATION forming part of Letters Patent No. 408,830, dated August 13, 1889.

Application filed March 28, 1889. Serial No. 305,081. (No model.)

To all whom it may concern:

Be it known that I, JULES DUBOIS, of Brooklyn, in the county of Kings and State of New York, have invented certain new and useful Improvements in Medallion or Photographic Watch-Cases; and I do hereby declare that the following is a full and exact description thereof, reference being had to the accompanying drawings, and to the letters of reference marked thereon, making a part of this specification.

My invention relates to devices whereby the case of a watch is utilized as a photograph-holder.

15 It has for its object to provide improved means for the retention of a photograph upon the watch-cap and for permitting either the concealment of the inclosed photograph by the case or its display through an opening 20 therein, at the pleasure of the owner; and it consists in the novel combination and arrangement for this purpose, and in connection with the cap and case of a watch, of the devices hereinafter described and claimed.

25 In the accompanying drawings, Figure 1 is an elevation of the rear face of a watch fitted with my improvement; Fig. 2, a view thereof in perspective with the case opened; and Fig. 3 a diametric section on an enlarged scale of 30 the cap and case with the latter closed, as in Fig. 1.

A represents the outer case of the watch, and B the cap-plate covering the works. Upon the outer face of the cap B a ring C is 35 soldered, said ring being slightly concaved or beveled about its inner periphery, so as to leave between its inner edge and the underlying face of the cap an annular re-entrant recess, as shown in Fig. 3, adapted to receive 40 and confine the rim of the thin sheet or film of paper, metal, or other suitable material upon which is impressed the photograph to be preserved. The rim of the photograph being cut to the proper size is sprung into the annular 45 recess, so that the photograph will fill the central circular space, the slightly-projecting rim C serving to protect it and to form a finishing frame or border therefor. Upon the opposite inner face of the hinged case A, which is 50 made to fit over and cover the cap B of the

watch in the customary manner, a corresponding ring D, preferably of the same diameter as the ring C, is soldered, its inner periphery being recessed to present a slight annular groove, as shown in Fig. 3.

55 A circular opening somewhat larger in diameter than that in the ring D is cut through the case A concentrically with said ring, and the peripheral edge of said opening is also inwardly grooved or recessed, as shown in Fig. 60 3. A circular plate E is provided to fit accurately within said opening. This plate is preferably made of a thickness which will admit of its engaging the periphery of the reinforcing-ring D, as well as that of the opening in the case, its rim being properly formed 65 with an annular recess or shoulder to adapt it to rest upon the shoulder formed by reason of the difference in the diameter of the openings in the ring and case, as shown in Fig. 3. 70

When the plate E is sprung into its seat in the case to close the opening therein, the case is made to present outwardly a solid unbroken appearance, and the inclosed photograph is concealed, unless the case be opened; 75 but by removing the plate the photograph in the underlying recess in the cap B remains clearly disclosed and constantly in view, the rabbeted rim encircling the opening, forming a very neat border for the picture.

80 A crystal may be fitted in the opening in the case in place of the concealing-plate E, and where variety is desired a set of plates bearing monograms or ornamental designs in diverse styles, and which may be incrusted 85 with various precious stones, &c., are furnished to be substituted for said plate E as occasion requires.

The two rings C and D are fitted to encircle the same axis, and the ring D may pass 90 within the ring C, or in some cases the two may be of the same diameter, so as to come into contact whenever the case is pressed inwardly abnormally and thereby afford it firm support, and said rings serve usefully to 95 strengthen both the cap and case of the watch.

I claim as my invention—

A watch having an inwardly-beveled ring secured centrally upon the outer face of its cap to form a retaining-seat for a photograph, 100

an outer case covering the cap, having an opening therein to register with said seat and which is encircled by an inwardly-projecting bead or ring, and a covering-plate fitting accurately within said opening to close it, substantially in the manner and for the purpose herein set forth.

In testimony whereof I have signed my name to this specification in the presence of two subscribing witnesses.

JULES DUBOIS.
